CLAIM

The ornamental design for an automobile tire, as shown and described.

DESCRIPTION

FIG. 1 is a perspective view of automobile tire showing our new design, it being understood that the tread pattern is repeated uniformly throughout the circumference of the tire;

FIG. 2 is a front elevation view thereof;

FIG. 3 is a side elevation view thereof, the opposite side being substantially a mirror image of that shown;

FIG. 4 is a greatly enlarged fragmentary plan view thereof; and,

FIG. 5 is an enlarged sectional view thereof taken along line 5—5 in FIG. 4.

FIG. 1

FIG. 2
